CONTAINER FOR DAIRY PRODUCTS OR THE LIKE

Clara Virginia Eicholtz, Midland, Mich., assignor to The Dow Chemical Company, Midland, Mich., a corporation of Delaware

Filed Sept. 19, 1962, Ser. No. 71,777

Term of patent 14 years

(Cl. D58—17)

FIGURE 1 is an elevational view of a container for dairy products or the like, showing my new design;

FIGURE 4 is a cross-sectional view thereof taken along reference line 4—4 of FIGURE 1 showing an embodiment which is characteristic throughout the views.

The dominant features of my design reside in the portions shown in full lines with the design being embossed on the surface around the side walls.

I claim:

The ornamental design for a container for dairy products or the like, substantially as shown and described.
